Henry W. Porter,
By his attorney Charles N. Gooding.

UNITED STATES PATENT OFFICE.

HENRY K. PORTER, OF BOSTON, MASSACHUSETTS.

CUTTING-TOOL.

1,145,082.

Specification of Letters Patent.

Patented July 6, 1915,

Application filed March 27, 1915. Serial No. 17,503.

To all whom it may concern:

Be it known that I, HENRY K. PORTER, a citizen of the United States, residing at Boston, in the county of Suffolk and State 5 of Massachusetts, have invented new and useful Improvements in Cutting-Tools, of which the following is a specification.

This invention relates to improvements in cutting tools and more particularly to 10 tools constructed and arranged to cut wires, bolts and the like, and is designed as an improvement over the type of bolt clipper disclosed in my U. S. Patent No. 909,663.

The object of this invention is to provide 15 a strong, durable cutting tool which is particularly adapted for use in warfare for severing and removing barbed wire entanglements, and to facilitate such use of the cutting tool, guide members have been provided which extend divergently outward 20 from the sides of the cutting members in order to assist in the guiding of the work to be cut between the cutting edges of the cutting levers. Said guide members terminate 25 at their outer extremities in hooks which enable the manipulator of the tool to pull tangled masses of wires from his path without necessitating the handling of said wires.

A further object of the invention is to 30 provide means whereby the device may be suspended from the belt.

The invention consists in the combination and arrangement of parts set forth in the following specification and particularly pointed out in the claims.

Referring to the drawings: Figure 1 is a plan view of a cutting tool embodying my invention, portions of the handles of said tool being broken away to save space in the 40 drawings. Fig. 2 is a side elevation, partly in section, of the cutting tool shown in Fig. 1. Fig. 3 is an underneath plan view of the guard, resilient abutment and ring, the cutting levers of said tool being illustrated in dotted lines. Fig. 4 is a section taken on the line 4—4 of Fig. 1. Fig. 5 is a view similar to Fig. 3 illustrating a modified form of guard and in which form the guard constitutes one of the straps of the cutting 45 tool. Fig. 6 is a section taken on the line 6—6 of Fig. 5.

Like numerals refer to like parts throughout the several views of the drawings.

In the drawings, 8, 8 represent a pair of 50 cutting levers which are pivotally connected together by suitable pivots 9, 9 extend-

ing through said levers 8 and two straps 10 and 11 arranged upon opposite faces of the cutting levers. The butt ends of the levers 8 are pivotally connected at 12 to 60 handles 13 which in turn are pivotally connected together at 14. The outer free ends of the cutting levers 8 are provided with cooperating edges 15. In cutting tools of this kind the jaws are not usually permitted to 65 be opened very wide, in fact, only slightly wider than the work for which the tool is designed to cut, consequently in reaching for work it is sometimes difficult to strike the same every time and especially would such 70 be true when the user of the device is in a hurry and the light is rather poor. To overcome such a difficulty a guard 16 has been provided, which guard is secured to one face of the cutting tool against the sides of 75 the cutting levers 8, 8. A recess 17 has been provided in the face of said guard adjacent said cutting levers to receive the strap 10, which is on that side of said levers. The guard 16 may be secured to the device in 80 any suitable manner. The preferred method however is to secure the same by a screw 18 arranged substantially at the center of said guard and extending into the strap 10.

The guard 16 embodies in its construction 85 a pair of guide members 19 which extend divergently from adjacent the strap 10 along the sides of the cutting levers 8 to points at substantial distances beyond the free ends of said cutting levers. The inner edges 20 of 90 said guide members are arranged to substantially align with the cutting edges 15 of the levers 8, when said levers are open, see Fig. 3, thus providing a wide and smooth approach to the cutting edges for guiding the 95 work therebetween. The outer extremities of the guide members 19 are turned outward relatively to each other and backward to form hooks 21, 21 which may be used to rip or pull wires from posts and to remove 100 tangled masses of wire from the path. As has been previously stated, the guide members 19 extend substantially from the strap 10 or from points adjacent the axes of the cutting levers. The opening 22 therefor 105 which is between said guide members and into which the wire is inserted extends beyond the inner ends 23, 23 of the cutting edges 15, especially when the jaws or levers 8 are open, as in Fig. 3. Should this be 110 permitted to remain so any small wire which might be inserted between the cutting edges

of said tool would be so far within the cutting edges that it would not be severed by the closing of said cutting levers. To limit the insertion of the work between said jaws and to permit the work to yield slightly during the cutting thereof an abutment 24 is arranged adjacent the inner end of the opening 22. Said abutment is preferably constructed of a resilient strip or strips of metal which are arranged transversely of the opening between the cutting edges 15 of said levers 8 and extend into recesses 25 formed upon the inner face of the guard 16, or in other words, the face of said guard which engages the faces of the levers 8. Abutments 26 are formed within said recesses and engage said resilient abutment at points a short distance from the ends thereof, thus providing a solid support for said resilient members and permitting straight and, if desired, flat sections of spring steel to be used and permitting the number thereof to be increased according to the resistance desired. Stops 27 are also formed within said recesses to engage the opposite face of the resilient abutment, said stops being at such distances from the abutments 26 that said resilient abutment 24 must be slightly deflected when inserted in order to securely hold the same in position.

For convenience in carrying the cutting tool from place to place a ring 28 has been pivotally mounted thereon, which ring may be attached to the belt of the person carrying the same, said ring being secured to the guard 16, preferably by means of a hook 29 formed integral with said guard and having its open portion 30 adjacent the sides of the levers 8. Thus when said guard is secured in place over the strap 10 the opening in said hook will be substantially closed and the ring 28 locked therein.

In Figs. 5 and 6 a modified form of guard is illustrated. In this form the base portion 31 of the guard 16' is adapted to take the place of the strap 10 and is secured in place against the cutting levers of the tool by the pivotal connecting means 9 shown in Fig. 4, which pass through holes 32 in the base 31. Otherwise the form illustrated in Fig. 5 is substantially as hereinbefore described.

Having thus described my invention what I claim and desire by Letters Patent to secure is:

1. A device of the class described having, in combination, a pair of pivoted cutting levers, and a pair of relatively stationary guide members for the work to be cut, said guide members extending divergently from points adjacent to the axes of said cutting levers along the sides of said levers to points substantially beyond the free ends thereof.

2. A device of the class described having, in combination, a pair of pivoted coöperating cutting levers, and a pair of relatively

stationary guide members for the work to be cut, said guide members extending divergently from points adjacent to the inner ends of the cutting edges of said cutting levers along the sides of said levers to substantial distances beyond the free ends of said cutting levers. 70

3. A device of the class described having, in combination a pair of pivoted coöperating cutting levers, and a pair of guide members for the work to be cut, said guide members being independent of said cutter levers and extending divergently from points adjacent to the axes of said cutting levers along the sides respectively of said levers to 80 substantial distances beyond the free ends of said cutting levers, the inner edges of said guide members being constructed and arranged to aline with the outer ends of the cutting edges of said cutting levers when 85 said levers are opened.

4. A device of the class described having, in combination, a pair of coöperating cutting levers, a pair of guide members for the work to be cut, said guide members being 90 constructed and arranged to direct said work between the cutting edges of said cutting levers, and a hook formed adjacent to the outer extremity of one of said guide members.

5. A device of the class described having, in combination a pair of pivoted cutting levers having coöperative cutting edges, and a pair of guide members for the work to be cut, said guide members extending divergently from points adjacent to the inner ends of said cutting edges along side said levers to substantial distances beyond the free ends of said cutting levers, the outer extremities of said guiding members being 100 turned outward relatively to each other and 105 backward to form hooks.

6. A device of the class described having, in combination, a pair of pivoted cutting levers having coöperating cutting edges, and a guard secured to said cutting levers, said guard having a pair of divergently arranged guide members for the work to be cut extending along the sides of said cutting levers from points adjacent to the inner ends of 110 said cutting edges to points substantially beyond the free ends of said cutting levers, the inner adjacent edges of said guide members being arranged to substantially aline with the cutting edges of said cutting levers 115 when said levers are opened.

7. A device of the class described having, in combination, a pair of pivoted cutting levers having coöperating cutting edges, a guard secured to said cutting levers, said 125 guard having a pair of divergently arranged guide members for the work to be cut, extending along the sides of said cutting levers from points adjacent to the inner ends of said cutting edges to points substantially be- 130

yond the free ends of said cutting levers, the inner adjacent edges of said guide members being arranged to substantially aline with the cutting edges of said cutting levers 5 when said levers are open, and an abutment mounted in said guard adjacent the inner extremities of the cutting edges of said cutting levers, said abutment being adapted to limit the insertion of the work between said 10 cutting levers.

8. A device of the class described having, in combination, a pair of pivoted cutting levers having coöperating cutting edges, a guard secured to said cutting levers, said 15 guard having a pair of divergently arranged guide members for the work to be cut extending along the sides of said cutting levers from points adjacent to the inner ends of 20 said cutting edges to points substantially beyond the free ends of said cutting levers, the inner adjacent edges of said guide members being arranged to substantially aline with the cutting edges of said cutting levers when said levers are open, said guide members 25 having recesses formed in the face thereof adjacent said cutting levers and upon opposite sides of the cutting edges of said levers, and a resilient abutment arranged within said recesses adjacent the inner extremities of said cutting edges adapted 30 to limit the insertion of the work between said cutting edges.

9. A device of the class described having, in combination, a pair of pivoted cutting levers having coöperating cutting edges, a guard secured to said cutting levers, said 35 guard having a pair of divergently arranged guide members for the work to be cut, extending along the sides of said cutting levers from points adjacent to the inner ends of 40 said cutting edges to points substantially beyond the free ends of said cutting levers, the inner adjacent edges of said guide members being arranged to substantially aline 45 with the cutting edges of said cutting levers, when said levers are open, said guide members having recesses formed adjacent the inner ends thereof, a substantially straight strip of resilient material arranged within 50 said recesses and extending transversely of the opening between the cutting edges of said cutting tool from one of said guide members to the other, and a pair of abutments for said resilient strip, formed upon 55 said guard and adapted to engage said strip at distances from opposite ends thereof, said resilient strip being constructed and arranged to limit the insertion of the work

between said cutting levers and to permit said work to yield during the cutting 60 thereof.

10. A device of the class described having, in combination, a pair of coöperating cutting levers, straps arranged upon opposite sides of said levers, a guard arranged 65 against one side of said cutting levers, said guard having a recess adapted to receive one of said straps, and a pair of guide members for the work to be cut, said guide members constituting a part of said guard and extending divergently from said strap along 70 the sides of said cutting levers to points at substantial distances from the free end of said cutting levers.

11. A device of the class described having, 75 in combination, a pair of coöperating cutting levers, a guard arranged against one side of said cutting levers, said guard having a pair of guide members for the work, extending divergently therefrom along the 80 sides of said cutting levers to points at substantial distances from the free ends of said cutting levers, a hook formed on said guard with the open portion thereof against the sides of said cutting levers and adapted to 85 be closed thereby, and a ring pivotally arranged within said hook and constituting a support for said device.

12. A device of the class described having, 90 in combination, a pair of coöperating cutting levers, a guard secured to said cutting levers, said guard having a pair of guide members for the work to be cut extending outwardly from points adjacent to the inner ends of said cutting levers, said guide members 95 having recesses formed adjacent to the inner ends of said cutting levers, a resilient member arranged with its opposite ends projecting into said recesses, an abutment formed in each of said recesses adapted to 100 engage the under face of said resilient member adjacent to the opposite ends thereof, and a second pair of abutments arranged upon opposite sides of said resilient member from that upon which said first named pair of 105 abutments are arranged and intermediate said first named abutments, said second pair of abutments being adapted to maintain said resilient member in contact with said first named abutments.

In testimony whereof I have hereunto set my hand in presence of a subscribing witness.

HENRY K. PORTER.
